UNITED STATES PATENT OFFICE.

CHARLES E. RANDALL, OF EVANSVILLE, INDIANA.

DESIGN FOR A PUZZLE.

43,204.

Specification for Design.

Patented Oct. 29, 1912.

Application filed June 12, 1911. Serial No. 632,960. Term of patent 3½ years.

To all whom it may concern:

Be it known that I, CHARLES E. RANDALL, a citizen of the United States, residing at Evansville, in the county of Vanderburgh and State of Indiana, have invented a new, original, and ornamental Design for Puzzles, of which the following is a specification, reference being had to the accompanying drawing, forming a part thereof.

The figure is a plan view of a puzzle illustrating my new design.

I claim:

The ornamental design for a puzzle, as shown.

In testimony whereof I herewith set my hand in the presence of two witnesses, at Evansville, Indiana, this 9th day of June, 1911.

CHARLES E. RANDALL.

Witnesses:

L. M. CURTIS,
F. C. GORE.
